(57) **CLAIM**

The ornamental design of a package with surface ornamentation, as shown and described.

DESCRIPTION

FIG. 1 is a top planar view of a package with surface ornamentation illustrating our new design, wherein the package is in an unfolded orientation;

FIG. 2 is a perspective view of a package with surface ornamentation illustrating our new design, wherein the package is a folded orientation;

FIG. 3 is a front side elevational view thereof;

FIG. 4 is a back side elevational view thereof;

FIG. 5 is a left side elevational view thereof;

FIG. 6 is a right side elevational view thereof; and,

FIG. 7 is a top planar view thereof.

The broken lines form no part of the claimed design.
